UNITED STATES PATENT OFFICE.

CHARLES GIBBS, OF NEW YORK, N. Y., ASSIGNOR TO UNDERWOOD TYPEWRITER COMPANY,
OF NEW YORK, N. Y., A CORPORATION OF NEW JERSEY.

TYPE-WRITING MACHINE.

No. 884,980.

Specification of Letters Patent. Patented April 14, 1908.

Application filed January 21, 1908. Serial No. 411,879.

To all whom it may concern:

Be it known that I, CHARLES GIBBS, a citizen of the United States, residing in borough of Bronx, city of New York, in the county of New York and State of New York, have invented certain new and useful Improvements in Type-Writing Machines, of which the following is a specification.

This invention relates to the type-bars and hangers of writing machines, and particularly to that class of hangers disclosed in my co-pending application No. 382,665, filed July 8, 1907, in which the hanger is in the form of a thin plate and is fastened in a radiating groove, each hanger having an individual lock or fastening device, in the form of a cam mounted in the same slot as the hanger and rotatable to lock and unlock the hanger.

The principal object of the present improvements is to facilitate the attachment and detachment of the hanger, and to provide for locking it securely in place.

I provide in a type-bar segment two pins or seat-rods for the hanger, each rod being curved to agree with the curvature of the segment, and each hanger having two hooks or hook-shaped slots to engage said seat-rods. By reason of this improvement, the hanger will set in place upon the segment temporarily while the locking cam is swung up clear therefrom, and it is rendered possible to attach and detach the hanger without being obstructed by said cam, owing to the use of the two seat-rods and two hooks; moreover the cam is enabled to lock the hanger securely in place.

In the accompanying drawings, Figure 1 is a sectional side elevation of a front strike writing machine of the Underwood class, showing my improvements applied thereto.

Fig. 2 is an elevation of the hanger and type-bar. Fig. 3 is a sectional fragmentary view of the segment, hanger and type-bar, the hanger locked in position. Fig. 4 is a view similar to Fig. 3, but illustrating the manner of detaching and attaching the hanger. Fig. 5 is a sectional front perspective view of a type-bar segment, hanger and type-bar, the hanger locked in position.

5) Type-bars 1 are caused by key-levers 2 and bell-cranks 3 to swing up about pivots 4 to strike against the front side of a platen 5; the type-bars being pivoted face-wise or in

any other suitable manner upon portions 6 of hangers 7, which are secured in radiating slots 8, formed in a segment 9, said portions 6 depending or extending outwardly and down from the segment. The slots or sockets 8 are cut completely through the bottom edge of the segment as seen clearly at Fig. 5, and the hangers 7 are in the form of thin plates which fit snugly in the slots 8. Preferably the cheeks or faces of the hanger are parallel throughout, and in order to seat the same securely, upper and lower curved rods 10, 11 are secured upon the rear side of the segment along its lower edge, and intersect the slotted portion of the segment. Said rods 10, 11 may be secured in any suitable manner, as by thrusting them endwise in undercut grooves 13, 14 formed in the rear of the segment. Each hanger has in its lower portion notches or slots 15, 16 which are hook-shaped at their upper portions, as at 17, 18, to catch over and fit tightly upon the seat-rods 10, 11, whereby the hanger and type-bar may be supported temporarily until locked by means of a device hereinafter described. A finger-piece 19 may project forward from the body of the hanger to be used in detaching the same from the segment.

The hangers are provided with individual locking devices, in this instance illustrated in the form of eccentric cams 20 fitting in the slots 8 and pivoted upon a common fulcrum 85 rod 21 mounted in an undercut groove formed in the segment above the hangers, the latter having bearings 22 to receive the eccentric under edges of the cams. Each of the latter has a handle 23 which may be 90 swung downwardly and forwardly to press down the hanger upon its seats 10, 11 the hanger being cammed immovably against both of said seats.

To detach the type-bar, it is only necessary 95 to swing up the cam lever, Fig. 4, when the finger-piece 19 may be grasped and the hanger 7 lifted to enable the hooks to clear the rods 10, 11, whereupon the hanger may be drawn forwardly out of the slot, Fig. 4, 100 this being an extremely quick operation. Each type-bar may have a heel 24 to press rearwardly the usual universal bar 25. It will be seen that the pressure of the cam 20 is in a downward direction, which not only 105 forces the hanger down upon the seats, but

also tends to swing the hanger rearwardly about the upper seat 10 into forcible engagement with the lower seat 11.

Having thus described my invention, I 5 claim:

1. A typewriting machine having a segment with two seats, a type-bar hanger with two hooks to engage the seats, and means to hold the hooks against said seats.
- 10 2. A typewriting machine having a segment, a type-bar hanger to engage it, and means to press the hanger home, said means being releasable and lying when released clear of the horizontal line of the hanger to 15 allow removal of the hanger horizontally.
- 15 3. A typewriting machine having a segment, a type-bar hanger to engage it, and means to press the hanger home, said means being releasable and lying when released 20 clear of the horizontal line of the hanger and above the same to allow removal of the hanger horizontally.
- 25 4. A typewriting machine having a segment, a type-bar hanger to engage it, and a releasable means above the hanger and engaging its upper edge to press the hanger home, said means lying when released clear above the upper edge of the hanger to allow removal of the hanger horizontally.
- 30 5. A type-bar hanger having two hooks to engage supporting points, and a substantially straight upper edge to be engaged by a clamping device.
- 35 6. A type-bar hanger having two hooks at its rear edge to engage supporting points, and a seat forward of such edge to be engaged by a clamping device.
- 40 7. A typewriting machine having a segment with two bearing points, a type-bar hanger having two downwardly facing hooks respectively to engage the bearing points, and means to press the hanger downward with the hooks against the bearing points.

CHARLES GIBBS.
